JOHN W. NEEDLES, OF KANSAS CITY, MISSOURI, ASSIGNOR OF ONE-HALF TO MILUS M. HOUSE, OF KANSAS CITY, MISSOURI.

DENTAL GRINDING DEVICE AND PROCESS.

Application filed March 15, 1926. Serial No. 94,763.

The present invention relates to dental appliances, and aims to provide a novel and efficient form of occlusal grinding device for use with articulating apparatus, such as is employed in the making of artificial dentures or like work. The principal object in view is to provide a mechanism which may be applied to articulators for the purpose of performing such a grinding operation as will 10 eliminate the locked relation which commonly exists between sets of artificial teeth, especially in central occlusion, my improved grinding operation resulting in a horizontal freedom of movement of the dentures in the 15 various positions of occlusion which they may assume.

For the purpose of performing this function, I have devised a grinding process, which consists in combining with the usual 20 grinding movements which characterize the common forms of articulators, a further component of grinding movement of such a character that the resultant movement will produce a grinding effect simulating that 25 due to the ordinary wear of natural teeth in their normal use, whereby the locked relation of the cusps is eliminated, since the necessary clearance is provided between them for permitting a proper horizontal 30 freedom of movement in all positions of occlusion. More specifically, the process is carried out by producing relative movement of the dentures in both directions laterally, as in the usual practice, but at the same time 35 a further component of movement, preferably rectilinear and angularly with reference to said lateral movement, is continuously imparted to one of the dentures in the same horizontal plane.

40 As carried out in practice, I have devised a grinding device adapted to be removably applied to the articulator, and including a movable plate having means of attachment to the upper denture and provided with an 45 actuating element adapted to effect the desired form of linear movement of said movable plate in the grinding operation. A suitable drive is provided for actuating said element, the arrangement of which is such that 50 one of the components of the relative movement of the dentures will correspond to a relative retrusive movement of the lower denture, starting with both dentures in normal central occlusion.

It is further sought to provide a device of 55 the character described in which provision is made for initially adjusting the position of the movable plate so that it will be symmetrically arranged with reference to what is known as the sagittal plane. 60

With the foregoing principal objects in view, as well as various minor objects which will appear in the course of the detailed description, the invention will now be described by reference to the accompanying 65 drawings illustrating one form of construction which I have devised for embodying the proposed improved mechanism, after which those features and combinations deemed to be novel will be particularly set forth and 70 claimed.

In the drawings—

Figure 1 is a side elevation, illustrating an 75 articulator having an occlusal grinding device constructed in accordance with the present invention;

Figure 2 is a plan view of the same;

Figure 3 is a central vertical section, taken 80 on the line III—III of Figure 2, the denture models being omitted;

Figure 4 is a horizontal section, taken on 85 the line IV—IV of Figure 1; and

Figure 5 is a detail section, taken on the line V—V of Figure 2.

Referring now to the drawings in detail, 90 these illustrate the improved occlusal grinder in its operative relation to a common and well known form of articulator now in commercial use, this articulator comprising a lower supporting frame 7 and an upper frame member 8 which is movably supported upon the lower frame 7 for pivotal sliding movement by means of what are known as rotation points 9, 10, engaging 95 suitably curved or inclined surfaces, as required for accommodating the movement of the upper frame member 8 in accordance with the different occlusal positions assumed by the upper denture 11 with reference to the lower denture 12 (see Figure 1). The 100 middle portion of the upper frame member 8 is engaged by a spring element 14 secured centrally to the upper portion of the lower frame member 7, said spring acting to maintain the dentures in yielding engagement in 105 all positions of the grinding operation.

To the lower frame member 7 is detachably secured, as by means of the clamping

screws 15, the usual denture model support 16 having its forward end provided with the inclined surface 17 for engagement with the lower end of the usual incisor guide pin 18 5 carrying the incisor guide element 19, the upper end of the pin 18 being designed to be clamped to the forward end of the usual upper model support which is attached to the upper frame 8, said upper model support, however, not being illustrated in the drawings, but being displaced by the grinding device forming the subject of the present application.

The improved grinding device herein illustrated is designed to be mounted in lieu of the upper denture model support in any of the common forms of articulators, the connection in the present construction to the upper articulator frame 8 being made by 15 means of the attaching screws 21 already present for the attachment of the upper model supporting arm, these screws 21 operating to secure the rear end of the fixed grinder plate 22, the forward end of which 20 is provided with a passage 23 for the upper end of the incisor pin 18, which is held in position by means of a clamping screw 24.

To the under face of the plate 22 is applied the movable grinder plate 25 which is 25 provided with retaining screws 26 for holding the plaster cast 27 that supports the upper denture model 11. The plate 25 is supported by means of a set of screws 28, the lower ends of which are supplied with nuts 30 engaging the under face of the plate 25; openings 30 are provided in the plate 22 of sufficient size to accommodate the movements of the screws 28 corresponding to the movement of the plate 25, the heads of said 35 screws being engaged by washers 31 supported by the margins of the openings 30, as clearly shown in Figure 2.

Secured centrally to the plate 25 is a vertical stub shaft 32 for journaling a belt 40 pulley 34 on the lower hub portion of which is formed an eccentric element 36, to which is fitted a rectangular block 38 mounted slidingly in a correspondingly shaped opening 40 in the plate 25, thereby forming a 45 transverse guideway for the block 38. At opposite sides of center, the contacting faces of the plates 22 and 25 are formed with longitudinal keyways for fitting rectangular key guides 42 which are rigid with one of 50 said plates, but slidingly engaged with the other, for thus accommodating the relative sliding movement thereof in response to the operation of the eccentric while confining said movement to a longitudinal or forward 55 and rearward movement, as will be obvious. It will be understood that a suitable belt drive (not shown) is designed to be applied to the pulley 34 for actuating the eccentric element thereby correspondingly actuating 60 the plate 25.

Adjacent to the front margin of the plate 25, the same is provided with the screw 45 projecting upward through an opening 46 of a size sufficient to receive the lock nut 47 mounted on the screw 45, when said nut 47 is turned down upon said screw 45. The function of the nut 47 is, by being clamped down within the opening 46, to initially position the plate 25 in its most rearward position which it may occupy relative to plate 22, or in what is referred to in practice as its posterior dead center position. After this initial adjustment, the nut 47 is turned up upon the screw 45, to thus release the plate 25 to the action of the eccentric 36 in carrying out the grinding operation.

In the operation of the improved grinder, after the upper model supporting arm has been removed from the upper frame member 8, the grinder device is secured in position by means of the screws 21, and the device is now adjusted so as to position the plate 25 at the most rearward limit of its movement as above explained, the nut 47 being lowered upon the screw 45 into the opening 46 for this purpose; this adjustment places the eccentric element 36 in forward position, that is, in front of the shaft 32, as represented in Figure 4. This is for the purpose of insuring that, as the grinding movement begins, with the dentures in central occlusion, the beginning of the movement of the plate 25 will be in a forward direction, corresponding to a relative retrusive movement of the lower denture.

After the mounting of both models in position, the nut 47 is raised into clamping engagement with the head of the screw 45, and power is applied by means of the belt attached to the pulley 34. The grinding operation is carried out first for the position of central occlusion, the operation of the eccentric element 36 resulting in a limited rectilinear movement, longitudinally forward and backward, as guided by the keys 42, the initial part of which movement is in a forward direction for the purpose of effecting a relative retrusive movement of the lower denture.

After grinding for the position for central occlusion, the articulator is adjusted to position the teeth for what is known as "end to end" biting relation, and the operation of grinding is carried out for this position, moving the articulator from time to time until central occlusion is reached. After this, the grinding process is carried out for right and left lateral occlusion, each time proceeding back to the position of central occlusion; and following this the same process is carried out for both positions of right and left lateral occlusion from protrusive occlusion, and back to the position of central occlusion.

As in all these different grinding posi-

tions, the action of the eccentric produces a component of linear movement in the same plate but in a different direction from the lateral incisor guide movements, which are 5 effected by hand as usual, the resultant movement produces a complete grinding action of the contacting cusp facets of the dentures (both front and rear faces), thus giving a perfect freedom from the locked 10 conditions not possible with ordinary articulator grinding.

From the foregoing it will be seen that I have provided a practical and efficient device and process for carrying out all of the 15 desired objects of the invention, and while I have illustrated what I now regard as the preferred mode of practicing the invention, I desire to reserve the right to make all such changes and modifications as may fairly fall 20 within the scope of the appended claims.

What I claim is:

1. A dental grinding process which consists in holding a pair of artificial dentures in occluded relation, and producing relative 25 movement of said dentures substantially horizontally in both lateral directions from central occlusion, while simultaneously imparting to one of said dentures a longitudinal rectilinear movement and positively 30 guiding said movement both forwardly and rearwardly.

2. An occlusal grinding device comprising the combination of means for holding a pair of dentures in occluded relation while permitting relative movement thereof in either 35 lateral direction, and means for imparting to one of said dentures, simultaneously with said lateral movement, a rectilinear movement of small amplitude and positively 40 guiding said movement in a longitudinal direction.

3. An occlusal grinding device for articulators comprising a plate provided with means for detachably connecting the plate to the frame of the articulator, a movable 45 denture supporting plate carried by said first plate, and means for imparting to said movable plate a reciprocatory movement of small amplitude and means for positively confining said movement to a fixed rectilinear path. 50

4. An occlusal grinding device for articulators comprising a plate provided with means for detachably connecting the plate to the frame of the articulator, a movable denture supporting plate carried by said first 55 plate, mechanical means for initially setting said movable plate at the most rearward limit of its movement, and means for imparting to said movable plate a reciprocatory movement of small amplitude. 60

5. An occlusal grinding device for articulators comprising a plate provided with means for detachably connecting the plate to the frame of the articulator, a movable denture supporting plate carried by said 65 first plate, and means comprising an eccentric element connected with said movable plate and coacting with said first plate for imparting to said movable plate a reciprocatory movement of small amplitude. 70

6. An occlusal grinding device for articulators, comprising a plate adapted to be secured to the articulator frame, a movable denture supporting plate carried by said first plate, eccentric means for imparting to said 75 movable plate a slight reciprocatory movement, and guide means mounted in and connecting said plates for positively confining said movement to a fixed path.

In witness whereof I hereunto affix my 80 signature.

JOHN W. NEEDLES.
